ARTIFICIAL ARM

Gilbert M. Motis, Burbank, and Joseph D. Chapman, Inglewood, Calif., assignors to Northrop Aircraft, Inc., Hawthorne, Calif., a corporation of California

Application April 6, 1948, Serial No. 19,375

9 Claims. (Cl. 3—12)

1

The present invention relates to artificial arms, and its primary object is to provide an arm having a wrist unit embodying passive, or manually pre-set flexion and extension of the wrist, together with automatic supination of the wrist driven member responsive to flexion of the forearm. More specifically, one of the objects of the invention is to provide a wrist unit having provision for both flexion-extension and pronation-supination movements, and in which the pronation-supination movement takes place beyond, or distally from the flexion-extension axis. This is the exact reverse of the arrangement employed in all prior devices of like nature known to us, and results in certain advantages which are impossible of attainment with the prior devices.

With the present invention, the wrist unit consists of a first member which is pivoted on the forearm component for swinging movement about the flexion-extension axis, and a second member which is journaled on the first member for rotation about the pronation-supination axis. Flexion and extension movements are passively controlled; i. e., the aforesaid first member of the wrist unit is adjusted angularly with respect to the forearm by using the other hand, or by pressing the same against the body or some stationary object such as a table, chair, or the like. When the wrist has been adjusted to the desired degree of flexion, the unit is locked and remained in fixed angular relationship to the forearm centerline until readjusted.

Pronation and supination movements of the wrist unit are coupled to forearm flexion, and are accomplished by means of a force-transmitting system which connects the rotatable member of the wrist to the upper arm component. This force-transmitting system is so constructed and arranged that when the forearm is flexed, the rotatable member of the wrist unit is automatically turned in a manner closely approximating the supination of the natural wrist. Since the rotatable member of the wrist unit is journaled on the swingable first member, flexion of the latter causes the supination axis to be positioned at an angle to the forearm centerline, and the hook or hand is thereafter caused to rotate about the inclined axis. When the wrist unit is thus positioned with a predetermined amount of flexion, the coordinated supination of the wrist member about the inclined axis as the forearm is flexed produces a leveling action at the hand or hook, enabling an eating utensil to be held level while it is being raised from the

2

table to the mouth. This self-leveling action greatly facilitates the process of eating, as well as the performance of other acts such as smoking, shaving, and the like, wherein the hand is raised to the face. Such self-leveling action cannot be obtained in prior devices having the flexion-extension axis located beyond the point at which supination begins, as this latter arrangement merely causes the flexed wrist and hand to be swung in an arcuate path about the fixed supination axis.

Another important object of the invention is to provide an artificial arm having a rotatable wrist member coupled to the upper arm component, whereby the wrist is supinated when the forearm is flexed; together with means for interrupting the drive to the wrist member and simultaneously locking the latter against rotation, so that the hook or hand can be selectively locked in any angular position about the pronation-supination axis.

Still a further object of the invention is to provide an arm of the class described, wherein the force-transmitting control member which operates the associated hook or hand passes through and is confined to a point representing the center about which all supination and flexion movements take place. By thus confining the path of the control member to the common center for both directions of movement of the wrist, the effective distance between the ends of the control member is held constant at all times, and operation of the hook or hand is not affected by the position of the same about either of its axes.

The foregoing and other objects and advantages of the present invention will become apparent to those skilled in the art upon consideration of the following detailed description of the preferred embodiment thereof, reference being had to the accompanying drawings, wherein:

Figure 1 is a partially broken away perspective view of an extended arm embodying the principles of the present invention;

Figure 2 is a cut away side view of the same; Figure 3 is a view similar to Figure 2, but with the forearm flexed, and the wrist unit turned on its pronation-supination axis;

Figure 4 is a sectional top plan view of the arm, as taken along the line 4—4 in Figure 2;

Figure 5 is a slightly enlarged sectional view taken along the line 5—5 in Figure 3;

Figure 6 is a fragmentary top plan view of the wrist unit and hook, showing the same in three positions of flexion;

Figure 7 is an enlarged sectional view taken along the line 7—7 in Figure 4, showing the wrist unit coupled to forearm flexion;

Figure 8 is a view similar to Figure 7, but showing the wrist unit disconnected from the upper arm component and locked against rotation; and

Figure 9 is an enlarged sectional view taken along the line 9—9 in Figure 4.

In the drawings, the reference numeral 10 designates the artificial arm in its entirety, said arm comprising an upper arm component 11, to which a forearm component 12 is connected by an elbow joint 13. Mounted on the outer end of the forearm member 12 is a wrist unit 14, the distal end of which is formed with an attach plate 15 that is adapted to receive a hook unit 16. In the embodiment illustrated, the upper arm component 11 consists of a stump socket 19 which is preferably made up of laminated plastic-impregnated fabric, formed to receive the stump in a snug-fitting engagement. The lower end of the stump socket 19 is molded over and bonded to an annular flange on a housing 20 forming a part of the elbow joint unit 13. The elbow unit 13 is the same as that disclosed in the copending application of Meyer Fishbein, et al., S. N. 747,690, filed May 13, 1947, to which reference may be had for details of construction and operation.

The housing 20 is generally cylindrical in shape, with a spherically curved outer end portion, and flats 21 formed on opposite sides thereof. A saddle 22 is mounted on the upper end of the forearm member 12, and has two laterally spaced ears 23 which are disposed to lie against the flats 21. Extending through the housing 20 and journaled in suitable bearings therein is a hinge pin 24, the ends of which project from the flats 21 and are rigidly connected to the ears 23. Inside the housing 20 is a locking device (not shown) for locking the forearm member in any one of a large number of closely spaced angular positions relative to the upper arm component 11.

The saddle 22 is semi-cylindrical in shape, and embraces the bottom half of the housing 20. A flange 25 projects from the outer end of the saddle 22, and bonded to the flange is a forearm shell 26, preferably of laminated plastic-impregnated fabric. An opening 27 is cut out of the top portion of the shell 26 adjacent the elbow joint to provide clearance for the housing 20 when the forearm member is flexed, as shown in Figure 3. At its outer end, the forearm shell 26 fits over and is bonded to an annular flange 30 projecting rearwardly from the back of a ring shaped member 31. Projecting forwardly from the top and bottom edges of the ring 31 are tongues 32 and 33 which provide support for the wrist unit 14.

The wrist unit 14 consists of a housing 34 which is pivoted on the forearm component 12 for angular movement about the flexion-extension axis, and the attach plate 15 that is journaled on the housing 34 for rotation about the pronation-supination axis. For the purposes of the present invention, the wrist-flexion-extension axis is considered to be disposed at right angles to the elbow hinge axis; while the pronation-supination axis extends generally forwardly from the flexion-extension axis and is perpendicular thereto. When the wrist unit 14 is straightened out, the pronation-supination axis substantially coincides with the longitudinal centerline of the forearm component 12, and when the wrist member 34 is swung around on the flexion-extension axis, the pronation-supination axis swings with it. Flexion

is the bending of the wrist to move the hand or hook toward the body; while extension is the opposite movement, tending to straighten the wrist, or move the hand away from the body. Pronation is the turning of the hand to a palm-down position; while supination is the turning of the hand to a palm-up position.

The hinge connection forming the flexion-extension axis of the wrist includes two vertically spaced tongues 36, 37 which extend rearwardly from the member 34 and overlap the tongues 32, 33, respectively. A pivot pin 40 is inserted into a hole in the top tongue 32 and is held therein by a set screw 39, said pin being journaled in a bushing 41 in tongue 36. In axial alignment with the pin 40 is another pivot pin 42 which is inserted into a hole in the bottom tongue 33 and is journaled in a bushing 43 in tongue 37. The pin 42 is held against turning by a set screw 44 (Figure 9) that is threaded into a tapped hole in a boss 45 formed on the inside surface of the tongue 33.

The wrist housing 34 is adapted to be locked in any one of several angularly spaced positions of flexion, and to this end a bifurcated locking lever 46 is pivoted at 47 on a blade-like projection 50 extending upwardly from the top end of pin 40. The lever 46 extends longitudinally of the wrist housing 34, and its rear end is pivotally connected at 51 to the head 52 of a pin 53 which is disposed within a hole 54 in the tongue 36. The bottom end of the pin 53 normally projects below the tongue 36 and is adapted to seat in any one of several holes 55 formed in the tongue 32, said holes being arranged in a circular arc about the axis of pin 40. In the preferred embodiment illustrated, there are five of the holes 55, the middle one of which gives a straight-out position for the wrist, and the others giving positions of 22½ and 45 degrees of flexion or extension to either side of the straight-out position. A spring 56 bears upwardly against the free end of the locking lever 46, urging the same into locking engagement.

The outer end of the cylindrical wrist housing 34 is threaded internally at 60 to receive the threaded barrel 61 of an annular bearing support member 62. Pressed into a cylindrical seat 63 in the member 62 is the outer race 64 of ball bearings 65. The inner race 66 of the ball bearings is mounted on the outer surface 70 of an annular flange 71 projecting rearwardly from the back of the attach plate 15. The inner surface of the flange 71 is threaded at 72 to receive a locking ring 73, the back end of which is provided with a radial flange 74 that engages the inner race 66 to clamp the latter in place.

Projecting rearwardly from the back side of the attach plate 15 through the center of the locking ring 73 is a tubular extension 75 having a central bore 76 formed therein. The tubular extension 75 might be formed integrally with the attach plate, as shown, or made as a separate part to facilitate manufacture. A sleeve bushing 80 is pressed into the bore 76, and slidably disposed within the bushing is a cylindrical coupling member 81, the outer end of which is formed with a socket 82 that is adapted to receive a companionate coupling member on the hook unit 16 so as to provide an operating connection therewith. The coupling member 81 has pins 78 projecting laterally from opposite sides thereof, and these pins slide in longitudinally extending grooves 79 in the bushing 80 to hold the coupling member against turning.

The hook unit 16 is adapted to be detachably mounted on the outer face of the attach plate 15,

and is provided with a housing 83 having a flanged, vertically extending coupling plate 84 on its back face which is adapted to be inserted down into companionate ways 85 formed in the outer face of the attach plate 15. A hook control coupling member (not shown) projects from the back face of the coupling plate 84 and is adapted to seat in the socket 82 of the coupling member 81 as the coupling plate 84 approaches full seating engagement with the attach plate 15; and the said coupling members are thereafter connected together to move as one. The coupling member on the unit 16 is operatively connected to a pivoted hook 86, and causes the latter to be closed against a stationary hook 87 when the interconnected coupling members are moved axially toward the right in the bore of bushing 80. The mechanism for actuating the pivoted hook 86 forms no part of the present invention, and therefore need not be described in further detail herein.

A control wire 90 is attached in any suitable manner to the inside of the coupling member 81 and extends rearwardly therefrom through the bushing 80 into the forearm shell 26. The rear end of the wire 90 is trained over the top of a small pulley 91 formed in one end of a hub 92 which is journaled for rotation on a transversely disposed tubular support 93. The tube 93 is held at its ends by two insert members 94 and 94' which are embedded in the side walls of the shell 26. One end of the tube 93 has a splined connection at 95 with the member 94', thereby locking the tube against rotation.

Projecting radially from the hub 92 alongside the small pulley 91 is an arm 96 having a pin 97 extending through a hole in its outer end. A fitting 100 attached to the end of control wire 90 is engaged on one projecting end of the pin 97, to form an anchorage for the wire. The other end of the pin 97 projects laterally from the opposite side of the arm 96 and is engaged by one end of a spring 101; the other end of the spring being anchored to a screw 102 which extends through the shell 26 and flange 25 of the saddle 22. The spring 101 pulls on the arm 96, exerting a counterclockwise torque on the hub 92. At the outer end of the hub 92 is a large pulley 103, and trained around the latter is a control cable 104. The cable 104 is attached to the pulley 103 and extends rearwardly from the top part thereof through the opening 27 and upwardly along the upper arm component 11. The cable 104 is preferably enclosed within a spring-wound housing (not shown) and is attached at its upper end to the usual shoulder harness, whereby a pull can be applied to the cable when the harnessed shoulder is shrugged downwardly and forwardly.

Automatic supination of the wrist member 15 responsive to forearm flexion is obtained by means of a force-transmitting system which will now be described. Pivoted at 105 on opposite sides of the elbow housing 20 are two side bars 106 which are connected at their front ends by a crossbar 107 to form a yoke 110. The crossbar 107 extends through and is slidable within a hole 111 (see Figures 7 and 8) formed in the outer end of a lever arm 112. The lever arm 112 is journaled intermediate its ends on the tubular support 93 and is slidable axially thereon. The bottom portion 113 of the lever arm, lying below the support 93, is in the form of a gear sector, and is provided with teeth 114 which are adapted to mesh with the teeth of a rack 115. The rack 115 is disposed generally parallel to the forearm

centerline, and is supported from below by a ball bearing roller 116 which is mounted on a pin 120 secured in aligned holes in the ends of two bracket arms 121 and 122. The bracket arms 121, 122 are mounted on and depend from the tubular support 93, and are locked against turning thereon by means of set screws 123. Slidably mounted on the tubular support 93 alongside the lever arm 112 is a downwardly extending stationary gear sector 124 having teeth 125 of the same pitch and pitch diameter as the teeth 114. The gear sector 124 is adapted to be shifted axially along the tubular support 93, carrying the lever arm 112 and rotatable gear sector 113 with it, and to this end a rod 126 is slidably disposed within the tubular support member. The ends of the rod 126 project a short distance beyond the ends of the tubular member 93 and have buttons 130 provided thereon, whereby the amputee can shift the rod in one direction or the other by pressing on one of the buttons. The stationary sector 124 is connected to the rod 126 by means of a screw 131 which is threaded into both of the members 124 and 126, and extends through axially elongated slots 132 in opposite sides of the tubular support member 93.

The lever arm 112 is confined on the opposite side by a ring 133 which is slidably mounted on the tubular support 93. The ring 133 is connected to the rod 126 by means of a screw 134 which is threaded into both of the members 133 and 126, and extends through axially elongated slots 135 in opposite sides of the tubular support member 93. Thus, when the rod 126 is shifted axially within the support member 93, the ring 133 and stationary gear sector 124 are moved with it, and since the lever arm 112 is confined between these members, the lever arm is also shifted axially with the rod 126. Detent means are provided for holding the rod 126 in either of its two positions, said detent means being preferably in the form of two balls 136, which are arranged at opposite ends of a diametrically extending hole in the rod 126. The balls 136 are both pressed outwardly by a spring and are adapted to seat in either of two notches 140 or 141 (see Figures 7 and 8) in the inside surface of the tubular member 93.

The rack 115 is clamped between two side bars 142 which extend down over the sides of the roller 116, thereby centering the rack on the roller. Downwardly extending projections 143 and 144 at the front and rear ends of the rack 115 are engageable with the roller 116 to limit the fore and aft travel of the rack.

The side bars 142 extend forwardly and upwardly from the rack 115 and are secured at their front ends to opposite sides of another rack 145. The teeth of the rack 145 are disposed along one side thereof, and mesh with a pinion 146 that is journaled on the pin 42. The rack 145 is confined on the other side by a ball bearing roller 150 which is mounted on a pin 151 extending down into a hole in the boss 45 of tongue 33.

Fixedly mounted on top of the pinion 146 is a bevel gear 152, the teeth of which mesh with another bevel gear 153 formed integrally with the tubular portion 75 at the rear end thereof. Thus, the wrist member 15 is rotated about the pronation-supination axis by bevel gears 152 and 153; the former being coaxial with the flexion-extension axis, and the latter being coaxial with the pronation-supination axis. Since the axes of the gears coincide with the axes of movement of the wrist member 15, the mesh of the gears

is unaffected by the position of the wrist member.

In order to maintain the path of the control wire 90 at a substantially constant length for all angular positions of the wrist member 15 about either of its axes, the control wire is confined between two laterally spaced rollers 154 which are arranged on opposite sides of the pronation-supination axis and slightly to the rear of the flexion-extension axis. The rollers 154 are spaced apart just slightly more than the diameter of the wire 90, as shown in Figure 5, and the plane of their axes is preferably located about .078" to the rear of the flexion-extension axis. This arrangement has been found to give a substantially constant length to the path of the control wire for all angular positions of the wrist housing 34 about the flexion-extension axis, and since the path of the control wire also lies directly on the pronation-supination axis, the length of the path of the control wire is unaffected by rotation of the wrist member 15 on its ball bearings 65. The rollers 154 are mounted on pins 155 which project upwardly from a crossbar 156 which is fixedly mounted at the top end of the pin 42. A pair of fiber links 160 and 161 connect the pins 155 above and below the rollers 154, forming a small rectangular opening bounded on the sides by the rollers 154 and on the top and bottom by links 160 and 161, through which the control wire 90 passes.

The operation of the arm is as follows: The wrist unit 16 is adjusted to the desired angular position about the flexion-extension axis by first releasing the lock, which is done by pressing downwardly on the free outer end of the locking lever 46 to unseat the pin 53 from its hole 55. The wrist housing 34 is then swung around to the desired position of flexion, and the locking lever 46 is released, allowing the pin 53 to seat in another hole 55. If the arm is to be used with wrist supination coupled to forearm flexion, the left hand button 130 on the rod 126 is pressed inwardly, shifting the rod to the right. Lever arm 112 is carried to the right with the rod 126, engaging the sector 113 with the rack 115, and at the same time, the stationary gear sector 124 is moved out of engagement with the rack 115. In this position, flexion of the forearm with respect to the upper arm causes the yoke 110 to move forwardly relative to the forearm component 12, rocking the lever arm 112 and gear sector 113 in a counterclockwise direction. This rotational movement of the gear sector 113 causes the rack 115 to be moved rearwardly, carrying the rack 145 with it and thereby rotating the pinion 146, and bevel gears 152, 153, which drives the wrist member 15 about its pronation-supination axis.

If it is desired to uncouple the wrist unit 14 from the upper arm component, the right hand button 130 on the rod 126 is pressed inwardly, shifting the movable gear sector 113 out of mesh with the rack 115, and carrying the stationary gear sector 124 into engagement therewith. With the rack 115 thus meshed with the stationary gear sector 124, the wrist member 15 is locked against rotation, and remains in a fixed position with respect to the forearm component 12. One of the advantages of the invention is that the angular position of the hook unit 16 about the pronation-supination axis can readily be adjusted by merely flexing the forearm while the gear sector 113 is meshed with the rack 115, until the hook unit is at the desired angle. The

rod 126 is then shifted to the left, locking the wrist member 15 in the adjusted position.

While we have shown and described in considerable detail what we believe to be the preferred form of our invention, it is to be understood that such details are not restrictive, and that various changes may be made in the shape and arrangement of the several parts without departing from the scope of the invention, as defined in the appended claims.

We claim:

1. In an artificial arm having an upper arm component and a forearm component swingably connected thereto by an elbow joint, a wrist unit comprising a member pivoted on the outer end of said forearm component for swinging movement about the wrist flexion-extension axis; another member journaled on said first-named member for rotation about the pronation-supination axis, said last-named member being spaced outwardly from and swingable about said flexion-extension axis, and driving means connected to said upper arm component and having a portion thereof coaxial with said flexion-extension axis for rotating said last-named member about said pronation-supination axis responsive to flexion and extension of said forearm component with respect to said upper arm component.
2. In an artificial arm having a forearm component, a wrist unit comprising a member pivoted on said forearm component for angular movement about the flexion-extension axis, another member journaled on said first-named member for rotation about the pronation-supination axis, said pronation-supination axis being swingable with said first-named member about said flexion-extension axis, said last-named member having a portion extending rearwardly through said first-named member coaxial with said pronation-supination axis, and rotatable driving means coaxial with said flexion-extension axis and engageable with said rearwardly extending portion to rotate said last-named member about said pronation-supination axis.
3. In an artificial arm having a forearm component, a wrist unit comprising a member pivoted on said forearm component for angular movement about the flexion-extension axis, another member journaled on said first-named member for rotation about the pronation-supination axis, said pronation-supination axis being swingable with said first-named member about said flexion-extension axis, said last-named member having a tubular portion extending rearwardly through said first-named member coaxial with said pronation-supination axis, a bevel gear fixedly mounted on said tubular portion, and another bevel gear journaled on said forearm component coaxial with said flexion-extension axis and meshing with said first-named bevel gear to rotate said last-named member about said pronation-supination axis.
4. In an artificial arm having a forearm component, a wrist unit comprising a member pivoted on said forearm component for angular movement about the flexion-extension axis, another member journaled on said first-named member for rotation about a pronation-supination axis intersecting said flexion-extension axis, the distal end of said last-named member being adapted to receive a hand or hook having operating mechanism provided therein, said last-named member having a tubular portion extending rearwardly through said first-named member coaxial

with said pronation-supination axis, a flexible control cable extending through the center of said tubular member and having means at the outer end thereof adapted for connection with said operating mechanism, a pair of laterally spaced rollers disposed on opposite sides of said cable closely adjacent said flexion-extension axis, said rollers confining the path of said cable to the intersection of said axes, whereby the length of said cable path remains constant for all angular positions of said last-named member, and rotatable driving means coaxial with said flexion-extension axis and engageable with said tubular portion to rotate said last-named member about said pronation-supination axis.

5. In an artificial arm having an upper arm component and a forearm component swingably connected thereto by an elbow joint, a wrist unit comprising a member mounted on said forearm component for angular adjustment about the wrist flexion-extension axis, another member journaled on said first-named member for rotation about the pronation-supination axis, said pronation-supination axis being swingable with said first-named member about said flexion-extension axis, driving means connected to said upper arm component and to said last-named member for rotating the latter about said pronation-supination axis responsive to flexion and extension of said forearm component, and means for disconnecting said driving means and locking said last-named member against rotation, whereby said last-named member can be locked in any angular position about said pronation-supination axis.

6. In an artificial arm having an upper arm component and a forearm component swingably connected thereto by an elbow joint, a wrist unit comprising a member mounted on said forearm component for angular adjustment about the wrist flexion-extension axis, another member journaled on said first-named member for rotation about the pronation-supination axis, said pronation-supination axis being swingable with said first-named member about said flexion-extension axis, a gear sector pivoted on said forearm component and slidably axially thereon, a link connecting said sector to said upper arm component, whereby said sector is rocked when said forearm component is flexed and extended, a rack adapted to be meshed with said sector and to be moved longitudinally thereby, said rack being connected with said last-named wrist member to rotate the latter about said pronation-supination axis, a non-rotatable gear sector disposed coaxial with said first-named sector and slidably axially therewith to engage said rack and hold the same against longitudinal movement, and means for sliding said two gear sectors axially so as to disengage one of them from said rack and engage the other one therewith, whereby said last-named wrist member may be operatively connected to said upper arm component for supination coupled to forearm flexion, or disconnected therefrom and locked against rotation.

7. In an artificial arm having a forearm component and an upper arm component swingably connected thereto by an elbow joint, a wrist unit comprising a member pivoted on said forearm component for angular movement about the wrist flexion-extension axis, another member journaled on said first-named member for rotation about a pronation-supination axis intersecting said flexion-extension axis, the distal end

of said last-named member being adapted to receive a hand or hook having operating mechanism provided therein, said last-named member having a tubular portion extending rearwardly through said first-named member coaxial with said pronation-supination axis, a flexible control cable extending through the center of said tubular member and having means at the outer end thereof adapted for connection with said operating mechanism, a pair of laterally spaced rollers disposed on opposite sides of said cable closely adjacent said flexion-extension axis, said rollers confining the path of said cable to the intersection of said axes, whereby the length of said cable path remains constant for all angular positions of said last-named member, a bevel gear fixedly mounted on the rear end of said tubular portion, another bevel gear journaled on said forearm component coaxial with said flexion-extension axis and meshing with said first-named bevel gear to rotate said last-named member about said pronation-supination axis, and means connected to said upper arm component for rotating said last-named bevel gear responsive to flexion and extension of said forearm component.

8. In an artificial arm having a forearm component and an upper arm component swingably connected thereto by an elbow joint, a wrist unit comprising a member pivoted on said forearm component for angular movement about the wrist flexion-extension axis, another member journaled on said first-named member for rotation about a pronation-supination axis intersecting said flexion-extension axis, the distal end of said last-named member being adapted to receive a hand or hook, said last-named member having a portion extending rearwardly through said first-named member coaxial with said pronation-supination axis, a bevel gear fixedly mounted on said rearwardly extending portion, another bevel gear journaled on said forearm component coaxial with said flexion-extension axis and meshing with said first-named bevel gear, a pinion fixed to said last-named bevel gear, a rack meshed with said pinion, means connecting said rack with said upper arm component, whereby flexion and extension of said forearm component causes said rack to be moved longitudinally, thereby rotating said bevel gears and causing said last-named wrist member to rotate about said pronation-supination axis, and means for disconnecting said rack from said upper arm component and locking the same against longitudinal movement, whereby said last-named member can be locked in any angular position about said pronation-supination axis.

9. In an artificial arm having a forearm component and an upper arm component swingably connected thereto by an elbow joint, a wrist unit comprising a member pivoted on said forearm component for angular movement about the wrist flexion-extension axis, another member journaled on said first-named member for rotation about a pronation-supination axis intersecting said flexion-extension axis, the distal end of said last-named member being adapted to receive a hand or hook, said last-named member having a portion extending rearwardly through said first-named member coaxial with said pronation-supination axis, a bevel gear fixedly mounted on said rearwardly extending portion, another bevel gear journaled on said forearm component coaxial with said flexion-extension axis and meshing with said first-named bevel gear, a pinion

fixed to said last-named bevel gear, a rack meshed with said pinion, a gear sector pivoted on said component and slidable axially into and out of mesh with said rack, a link connecting said sector to said upper arm component, whereby said sector is rocked when said forearm component is flexed and extended, a non-rotatable gear sector disposed coaxial with said first-named sector and slidable axially therewith to engage said rack and hold the same against longitudinal movement, and means for simultaneously sliding said two gear sectors axially so as to disengage one of them from said rack and engage the other one therewith, whereby said last-named wrist member may be operatively connected to said upper arm component for supination coupled to forearm flexion, or disconnected therefrom

and locked against rotation, with said hand or hook in any selected angular position about said pronation-supination axis.
